UNITED STATES PATENT OFFICE.

ERNST UHLICH, OF GRÜNA, GERMANY.

DESIGN FOR A LACE GLOVE.

No. 40,226.

Specification for Design.

Patented Aug. 10, 1909.

Application filed April 7, 1909. Serial No. 488,534. Term of patent 7 years.

To all whom it may concern:

Be it known that I, ERNST UHLICH, a subject of the King of Saxony, residing at Grünna, Saxony, Germany, have invented a new, original, and ornamental Design for Lace Gloves, of which the following is a specification, reference being had to the accompanying drawing, forming part thereof.

The figure is a plan view of a lace glove, showing my new design.

I claim:

The ornamental design for a lace glove, as shown.

ERNST UHLICH.
